UNITED STATES PATENT OFFICE.

HAAKON A. MARTIN, OF DAYTON, OHIO, ASSIGNOR TO THE NATIONAL CASH REGISTER COMPANY, OF DAYTON, OHIO, A CORPORATION OF OHIO, (INCORPORATED IN 1906.)

TOTAL-PRINTING CASH-REGISTER.

1,188,467.

Specification of Letters Patent. Patented June 27, 1916.

Application filed July 17, 1913. Serial No. 779,505.

To all whom it may concern:

Be it known that I, HAAKON A. MARTIN, a citizen of the United States, residing at Dayton, in the county of Montgomery and State of Ohio, have invented certain new and useful Improvements in Total-Printing Cash-Registers, of which I declare the following to be a full, clear, and exact description.

10 The present invention relates to improvements in cash registers and more particularly to registers of the class adapted to print, indicate, and register items of transactions and also adapted to print the totals 15 thereof appearing on the totalizer.

The particular object of the present invention is to provide a new form of differential mechanism for a cash register or analogous machine, and particularly one which is positive in movement and may readily be employed in the printing of totals appearing on the totalizer.

A number of machines have been designed in which the totals appearing on the totalizer may be printed on the record strip, but in the majority of those machines the differential devices are non-positive in movement. In the present invention the movement of the differential devices is at all 30 times positive thereby eliminating the possibilities of mis-operation.

A further object of the invention is to provide an improved form of differential mechanism, the adjustment of which is effected by a constant movement of the totalizer, and which, when adjusted, serves to actuate the totalizer during the remaining portion of the constant movement.

A further object of the invention is to 40 provide an improved form of indicating mechanism wherein the indicators are normally disconnected from the differential devices whereby an indicator will not be connected to or moved by the differential device 45 vice unless a key in the bank appropriate thereto is depressed.

A further object of the invention is to provide an improved form of total printing mechanism employing a novel form of type carriers provided with two sets of type, one of which may be used for the printing of items and the other set being used for the printing of totals.

With these and incidental objects in view,

the invention consists in certain novel features of construction and combinations of parts, the essential elements of which are set forth in appended claims, and a preferred form of embodiment of which is hereinafter described with reference to the drawings which accompany and form part of the specification.

Figure 1 is a cross section of a machine embodying the present invention on a reduced scale. Fig. 2 is a detail view of one of the detents employed in the keyboard mechanism and drawn on the same scale as Fig. 1. Fig. 3 is a large scale detail sectional view of the totalizer and transfer mechanisms. Fig. 4 is a full sized detail sectional view showing the differential mechanism and totalizer and connections effective in the printing of totals. Fig. 5 is a detail top plan of the totalizer mechanism and transfer devices. Fig. 6 is a detail perspective view of only the transfer devices. Figs. 7, 8 and 9 are detail views of cams for operating printing platen, totalizer elevating means and indicator restoring means respectively. Fig. 10 is a left hand end view of the machine showing the improved form of printing mechanism and connections employed for printing of totals in total printing position. Fig. 11 is a detail top view of the indicating mechanism and connections. Fig. 12 is a detail view of the controlling arm for the type carrier actuating racks. Fig. 13 is a detail view of the cam for operating the indicator coupling mechanism. Fig. 14 is a detail sectional view of a total key and connecting mechanism.

General operation.—Described in general terms the machine comprises a plurality of banks of depressible controlling keys which, when depressed, serve differentially to control the adjustment of differential mechanism.

The totalizer mechanism is mounted in a movable frame which is adapted to be given a constant movement of reciprocation at each operation of the machine which movement is relative to a series of actuators. Each actuator is appropriate to a bank of keys and is adapted to be adjusted to a position predetermined by the depression of one of the amount keys, during the constant movement which is given to the totalizer mechanism. In the printing of items the

totalizer is adapted first to act to adjust the actuators to the position predetermined by the depression of the amount keys, and then to be actuated by the actuators when so adjusted.

Cash registers and analogous devices have been designed in which the totalizer is given a constant movement relative to the actuators, during which movement the actuators 10 serve to actuate said totalizer but it is thought that this is the first instance in which the constant movement is employed for the dual purpose of adjusting the actuators and then actuating the totalizer 15 thereby when adjusted.

For the purpose of printing totals appearing on the totalizer, a total key and connections are provided whereby the operation of the totalizer and actuators is to some extent reversed in that the first part of the constant movement of the totalizer serves to reset the elements thereof to normal zero position while the remaining portion of said constant movement will serve to adjust the 25 actuators to an extent commensurate to the value of the amount which was cleared from the totalizer.

The invention further includes an improved form of transfer mechanism normally stationary and effective upon the restoring stroke of the totalizer successively to actuate any of the transfer devices which have been tripped during the operating stroke of the totalizer. The transfer devices as stated are normally stationary but upon an operation of the total key they are disabled, as it is obvious that transfers tripped in the resetting of the counter to 35 normal zero position should not be operated.

The invention also comprises improvements in the printing mechanism whereby the type carriers or printing elements are adapted to be adjusted in reverse directions 45 for the printing of items and totals. The type carriers are provided with two sets of type which may be of different form so as to enable an operator readily to distinguish a printed total from a printed item. An improved form of indicating mechanism and connections is also provided wherein the indicators are normally disconnected from the actuators of the differential mechanism. Each indicator is appropriate to one of the banks of amount keys and connections are so designed as to require an operation of one of the keys in the appropriate bank before an indicator is operatively connected with its appropriate actuator. It will readily be seen that with this construction a great deal of power required in operating the machine is eliminated in that no indicator will be moved unless a key in its appropriate bank has been adjusted. This is of particular advantage in

the printing of totals as the indicators will not publicly disclose the total as in so many forms of total printing cash registers.

Keyboard mechanism.—In a preferred embodiment of the present invention a series of banks of depressible keys is employed, but as all of said banks and their coöperating mechanisms are substantial duplicates only one bank will be shown and described herein. Each of the banks of keys comprises a plurality of depressible keys 20 (see Fig. 1) which serve to control the extent of adjustment of its appropriate actuator. Each of the keys when depressed also serves to adjust the connecting mechanism 70 intermediate its appropriate actuator and indicator whereby said indicator will be coupled to the actuator upon an operation of the machine. When one of the keys 20 is depressed it is locked in depressed position by a detent plate 21 (Fig. 2) of well known form which is provided with the series of locking hooks 22 adapted to co-operate with a pin 23 carried by each of said keys 20 whereby a key is locked in depressed position. The detent 21 is normally held in elevated position by spring means, not shown. The form of detent mechanism shown is well known in the art and needs no further detailed description or 80 illustration in the present application. Co-operating with the pins 23 on the amount keys 20 of each bank is a cam plate 24 (see Fig. 1) provided with a series of inclined slots 25 each in position to be engaged by 85 a pin 23 upon the depression of its appropriate key. At its upper end the plate 24 is provided with a V-shaped cam notch 26 for the purpose of controlling the indicator connecting mechanism in a manner herein- 90 after described.

Differential mechanism.—As is usual in machines of this type the keys 20 serve to control the differential adjustment of the actuators comprising the differential mechanism of the machine. In the present machine the actuators (see Figs. 1 and 3) comprise oscillatory members 25 loosely mounted on a rock shaft 26 extending between the frames of the machine. Each of the 100 members 25 is provided with rack teeth 27 for actuating the indicator and printer connections and rack teeth 28 coöperating with the totalizer elements. Slidably mounted on the member 25 is an arm 29 having a 105 forwardly extending portion 30 which is adapted to coöperate with the keys 20 when depressed. The arm 29 is provided with an elongated slot 31 surrounding a pin 32 carried by the member 25 which serves as a 110 sliding bearing for the arm 29. The arm 29 is normally held in the position shown in Fig. 1 by a spring 33 interconnected to a pin 34 carried by the arm 29 and a pin 35 carried by the member 25. The arm 29 is 115

curved downwardly and rearwardly as shown in said Fig. 1 and at its lower rear-most end is pivotally connected at 36 to a bell crank 37 a downwardly extending arm of which is formed with the hook portion 38. The other arm of the bell crank 37 is formed on an arc as at 39 for a purpose hereinafter described. The bell crank 37 is pivoted at 40 to the actuator member 25 and the hook formed portion 38 of the one arm thereof normally extends beyond the teeth 28 formed on said actuator member 25. The actuators 25 are adjusted in a novel manner. Certain patents belonging to the art to which the present application pertains show actuators which are driven differentially by the operating mechanism of the machine to actuate a totalizer which is adapted to be thrown into and out of engagement with the actuators at the proper time. In other patents there are shown forms of actuating means which are first differentially adjusted and the totalizer is then engaged therewith and given a constant movement relative to the actuators during which movement the totalizer elements are actuated to an extent commensurate with the adjustment of the actuators. In the present machine, however, the totalizer is given a movement which is constant, and relative to the actuators on every operation of the machine. In the operation of entering an item on the totalizer the totalizer elements are locked to the actuators and during the first part of said constant movement the actuators will be differentially adjusted until arrested by engagement of the actuators with the depressed keys. The engagement of the actuators with the depressed keys serves to disable the locking means and arrest the actuators. Consequently during the remaining portion of the constant movement of the totalizer the totalizing elements will be actuated to an extent commensurate to the differential adjustment given to the actuators.

Totalizer mechanism.—The totalizer in the present application comprises a plurality of totalizer elements 41 which are in the form of pinions having ten teeth and are mounted to rotate on a shaft 42 carried by two arms 43 pivotally mounted on a rock shaft 44 extending between two plates 45 constituting a swinging frame which is pivotally hung on the cross shaft 26. Pivotally connected at 46 to one of the plates 45 is a pitman 47 bifurcated at its upper end to straddle a main operating shaft 48 and carrying an anti-friction roller 49 projecting into a cam slot 50 formed in a box cam 51 fast to the operating shaft 48. The shaft is adapted to be given a single complete rotation at each operation of the machine by any desired form of operating means. It will readily be seen that upon a

rotation of the operating shaft 48 and cam 51 the totalizer carrying frame comprising the side plates 45 will be given a constant movement whereby said totalizer will be given the above mentioned constant movement relative to all of the actuators. The shaft 42 carrying the totalizer elements 41 projects slightly beyond the carrying arms 43 and plates 45, into slots 52 formed on an arc in plates 53 pivotally mounted on a cross shaft 54 mounted in the frames of the machine. The plates 53 are adapted to be rocked about the shaft 54 at each operation of the machine to elevate the shaft 42 and rock the arms 43 carrying said shaft about the supporting rod 44 whereby the teeth of the totalizer elements 41 will be caused to engage with the actuating teeth 28 formed on the actuators.

The plates 53 are adapted to be elevated in the following manner. Fast on the shaft 48 is a cam 55 (Fig. 8) provided with the cam slot 56 in which projects an anti-friction roller 57 carried by a pitman 58. The pitman 58 is bifurcated at its upper end to straddle the shaft 48 and is pivoted at its lower end at 59 to an arm 60 fast to a rock shaft 61 which is adapted to be rocked at each operation of the machine through the connections just described. Also fast on the shaft 51 are a pair of rearwardly extending arms 62 carrying at their rear ends roller 63 projecting into elongated slots 64 formed in the elevating plates 53. It will therefore be seen that when the shaft 61 is rocked at each operation of the machine, as stated, the plates 53 will be raised to elevate the totalizer into engagement with the actuators 25.

The cams 55 and 51 are so timed that the totalizer will be elevated into operative engagement with the actuators 25 before the cam 51 will become effective to cause the constant movement of the totalizer carrying frame. The constant movement of the totalizer frame is of a reciprocatory nature and comprises a forward actuating stroke and a rearward restoring stroke, and the movement of the totalizer will hereinafter be referred to in that manner in both the specification and claims.

Immediately upon the completion of the forward actuating stroke of the totalizer carrying frame the cam 55 will become effective to rock the shaft 61 back to its normal position thereby lowering the plate 53 and withdrawing the totalizer from engagement with the actuators. The cam 51 will then become effective to effect the restoring movement of the totalizer carrying frame. During the entire constant movement of the totalizer carrying frame it will readily be seen that the totalizer will be controlled by the arc shaped slots 52 formed in the plates 53.

When the totalizer elements 41 are elevated into engagement with the teeth 28 of the actuators 25 the hook shaped portion 38 of the bell crank 37 above mentioned will engage in one of the deep notches between the teeth of the totalizer pinions 41. When the constant movement of the totalizer carrying frame and the totalizer is then begun the totalizing pinions will have a tendency to rotate about the shaft 42 but the rotation of said pinions will be prevented by reason of the engagement of the hook shaped portion 38 of the bell crank 37, as just described, with the pinions 41. Consequently the actuators 25 will be moved during said constant movement. The movement of the actuators 25, however, as before stated, is adapted to be arrested by the engagement of the projecting portion 30 of the arm 29 with one of the depressed keys 20. When said engagement occurs the arm 29 will be forced downwardly against the tension of spring 33 and through the pivotal connection 36 with the bell crank 37 said bell crank will be rocked about its pivot 40 thereby disengaging its hook-shaped portion 38 from the totalizer element 41. It will be seen that as soon as the pin 32 reaches the upper end of the slot 31 formed in the arm 29 the movement of the corresponding actuator 25 will be completely arrested. However, as the corresponding totalizer element 41 is then unlocked the said element will be free to rotate during the remaining portion of the actuating stroke of the totalizer. The totalizer element will therefore be actuated to an extent complementary to the extent of adjustment of the actuator and commensurate to the value of the keys depressed.

The keys 20 are arranged in banks of nine each, as shown in Fig. 1, and are numbered from one to nine, the key at the top of said bank being number "1" while the key at the bottom of said bank being numbered "9". It will therefore be seen that if the "1" key is depressed and the machine operated the actuator will be given nine steps of movement before it is arrested during which movement the totalizer element 41 appropriate to the actuator 25, which is appropriate to the key depressed, will be constantly locked to the actuator and consequently rotation of said totalizer element will be effected. However as soon as any actuator 25 is arrested by engagement with the "1" key the locking engagement between the actuator and its totalizer element will be disabled. Upon the continued movement of the totalizer element in its constant actuating stroke the totalizer element will be rotated one step thereby adding one on the same. The actuator 25 is capable of receiving ten steps of movement and the totalizer carrying frame is given a movement equal in operating effect to the complete movement of the actuator. Consequently if no key in the bank is pressed the actuator will be carried the full ten steps of movement by reason of the fact that the same will be constantly locked to the totalizer element 41 during the entire operating stroke of the constant movement given to the totalizer carrying frame. If, however, the "9" key is depressed the actuator will be arrested at the completion of one step of movement there being a slight portion of movement given the actuator because of the slot and pin connection between said actuator and the arm 29. The projection 30 it will be noted is normally in position to engage the "9" key when depressed immediately upon the beginning of an operation of the machine. The totalizer element will then be operated during the remaining nine steps of movement of the totalizer carrying frame. The actuators 25 which have been adjusted during an operation of the machine are restored to normal zero position in the following manner. Each of the plates 45 is formed with a forwardly extending arm 451 carrying a cross rod 452 extending across the top of all of the spokes 453 of the actuators 25. It will readily be seen that during the actuating stroke of the totalizer carrying frame the rod 452 will move away from the spokes 453 thereby permitting adjustment of the actuators. However, on the restoring stroke of the totalizer carrying frame, the rod 453 will engage the spokes of the adjusted actuators and thereby restore the same to normal zero position.

Transfer mechanism.—As is customary in machines of the present type, transfer mechanism is provided for transferring a unit from a wheel of lower order to a wheel of higher order upon the completion of a rotation of the wheel of lower order. The novel form of transfer mechanism provided in the present machine consists of the following constructions. Each of the totalizer elements 41 is provided with an enlarged tooth 65 (see Figs. 1, 3 and 6) which upon a complete rotation of the totalizer element is adapted to engage the forward end of a transfer arm 66 loosely pivoted on the shaft 44 hereinbefore referred to. Carried by the transfer arm 66 is a pin 67 which is adapted to engage a hook member 68 carried by a sleeve 69 surrounding a stud 70 carried by a bell crank 71 pivotally mounted on a rod 72. The rod 72 is supported at each end by a pair of links 720 and 721, the former of which is pivotally connected at one end to the lower ends of the totalizer frame plates and the latter to the arms 43. The other ends of the links unite to support the rod 72. Fast to the other end of the sleeve 69 is a member 77 carrying a tooth 74 adjacent the wheel of next higher order. The member 77 is formed with two locking notches 125

78, coöperating with a locking and alining pawl 79 pivoted at 80 to the bell crank 71 and constantly held in locking position by a spring 81. The normal position of the 5 parts just described is shown in Figs. 1 and 3.

Upon a complete rotation of a totalizer element 41, the enlarged tooth 65 thereof will engage the appropriate transfer arm 10 66 and rock the same about the shaft 44. This movement of the transfer arm 66, will, through the medium of the pin 67, rock the hook member 68 in the direction of the arrow (Fig. 6) and with it the sleeve 69 and 15 member 77 thereby causing the locking and alining pawl 79 to engage the other one of the pair of notches 78 shown in said Fig. 2. In the moved position of the member 77, the tooth 74 carried thereby will be in a position 20 to engage a tooth of the totalizer element of higher order upon the rocking movement of the bell crank 71 in the counter clockwise direction about the shaft 72 as viewed in Fig. 3. This rocking movement of the bell 25 crank 71 is effected in the following manner: Mounted adjacent the totalizer mechanism, and formed concentric with the arc of movement of the totalizer in its constant movement, are a series of transfer bars 81 all of 30 which are pivoted at their rear ends on a cross rod 82, and at their forward ends are formed with elongated slots 83 surrounding a rod 84 carried by a pair of arms 85 fast on a rock shaft 86. Each of the transfer 35 bars 81 is formed with a bevel lug 87. As shown in Fig. 5 there are five sets of transfer devices as there are only six totalizer wheels provided in the machine as shown. Each of the bell cranks 71 carries on its 40 rearwardly extending arm, an anti-friction roller 88. There are provided as many transfer bars 81 as there are transfer devices and each of the bars 81 is appropriate to one said transfer devices and its lug 87 45 is normally in the path of movement of the anti-friction roller 88 during the restoring stroke of the constant movement of the totalizer. When the totalizer is elevated into engagement with the rack teeth 28 of the 50 actuators 25 the anti-friction roller 88 will be held clear of the lugs 87 throughout the actuating stroke. However on the restoring stroke of the totalizer the same is lowered out of engagement with the actuator as 55 hereinbefore described and the anti-friction rollers 88 are correspondingly lowered so as to be in a position to be engaged by the lugs 87 during the restoring stroke. When the restoring stroke is effected the anti-friction 60 rollers 88 will be engaged by the lugs 87 and bell cranks 71 will consequently be rocked about their pivots 73 to effect a transfer by those of the transfer devices which have been tripped during the actuating stroke.

65 As is usual in totalizing devices, the trans-

fer actuating devices are arranged to be operated in succession so as to eliminate the possibility of loss of transfer where several wheels in successive order stand at nine and a transfer is to be carried across all of said 70 wheels. This successive operation is effected by locating the lugs 87 on the transfer bars 81 in the order shown in Figs. 1, 3 and 4, in which position it will readily be seen that the anti-friction rollers 88 will be engaged in 75 succession from lower to higher order. When the bell cranks 71 are rocked about their pivot in the manner just described, the teeth 74 of their tripped transfer devices will engage the teeth of their totalizer pinions 41 and rotate said pinions to the extent of one tooth, or a unit. The purpose of mounting the forward ends of the transfer bars 81 on the bar 84 carried by the rocking frame comprising the side frames 85 and 80 rock shaft 86 is for the purpose of disabling the transfers during the total printing operation in a manner hereinafter described.

Pivots mounted on a bar 89, carried by and between the plates 45 are a series of 90 alining pawls 90 the rearward ends of which are constantly in engagement with the teeth of the totalizer wheels and are held in position by springs 91 interposed between shoulders 92 formed on the forward ends of said pawls and a bar 93 also extending between the side plates of the rocking totalizer frame 45. The pawls 90 therefore serve at all times to hold the totalizer wheels 41 in adjusted position. The rearward end of the 100 bell cranks 71 are formed with downwardly extending arms 94 which are adapted to strike against a cross bar 95 extending between the bell cranks. Springs 96, one end of which is connected to pins 97 carried by 105 each of the bell cranks 71 and the other end to the cross bar 95, tend to hold the bell cranks 71 in normal position. At the end of the restoring stroke of the totalizer after all of the tripper transfers have been actuated to turn in the transfers, the hook portions 68 of the transfer devices will be engaged by a series of arms 970 rigidly mounted on a cross rod 98 carried by the member 53. When the hook portions 68 of the 110 tripped transfer devices engage the arms 970 the hooks 68 will be rocked about the studs 70 and through the medium of the sleeve 69 will rock the transfer plates 77 to normal position and cause the locking and 115 alining pawl 79 again to engage the forward one of the two notches 78 so as to hold the transfer devices in normal position.

Indicating mechanism.—As hereinbefore stated, the actuators 25 are each provided 120 with ratchet teeth 27 for actuating the indicating and printing devices. In the operation of the indicating devices the following mechanism is employed: Each of the actuators 25 is constantly in engagement with an 125

indicator actuating gear 100 loosely mounted on a rock shaft 101. Adjacent each of the gears 100 is a companion gear 102 of exactly the same size as the gears 100 and also 5 loosely mounted on the rock shaft 101. Each of the gears 102 is constantly in mesh with a pinion 103 fast to an indicator 104 all of which indicators 104 and pinions 103 are loosely mounted on a shaft 105 extending 10 across the top of the machine. Each of the indicators 104 is appropriate to one of the banks of keys 20 but, as will be seen from the foregoing description, is normally disconnected from the indicator operating means. 15 Mechanism is provided whereby an indicator is only connected to its appropriate indicator operating means when a key in its appropriate bank is operated. The connecting mechanism comprises a broad pinion 106 20 carried by a bell crank 107 loosely mounted on the cross shaft 105. Each broad pinion 106 is mounted adjacent its two companion gears 100 and 102 and is of sufficient width to engage both of said gears simultaneously 25 upon a rocking movement of the bell crank 107. The bell cranks 107 are normally yieldingly held in the position shown in Fig. 1 by springs 108. The forwardly extending arms 109 of the bell cranks 107 are formed 30 with a small flange 110 which normally stand in the path of movement of arms 111 also pivoted loosely on a cross shaft 105. Each of the arms 111 carry a pair of studs 112 and 113 the latter being normally in 35 engagement with a V-shaped notch 26 formed in the cam plates 24 of its appropriate bank of keys 20. When one of the keys in a bank is depressed, it will engage and move the appropriate cam plate 24, 40 which movement will effect the rocking of the arm 111 about the shaft 105 by reason of the engagement of the rear bevel wall 114, of the V-shaped notch 26 with the stud 113. When the arm 111 is thus moved the stud 45 112 will be in the path of the movement of a beveled face 115 formed on a curved arm 116 fast on the rock shaft 101. In this position of the arm 111 said arm will also be in engagement with the flange 110 carried by 50 the arm 109 of the bell crank 107. Upon the operation of the machine the shaft 101 will be given a slight oscillation through the medium of an arm 117 fast on the shaft 101 and pivotally connected to a pitman 118 55 extending downwardly and bifurcated at its lower end to straddle the main operating shaft 48. The pitman 118 carries an anti-friction roller 119 (Fig. 13) adapted to cooperate with an eccentric cam slot 120 60 formed in a box cam 121 fast on said operating shaft 48. When the shaft 101 is so rocked at each operation of the machine, the beveled face 115 of the curved arms 116 will engage the studs 112 of any of the arms 111 65 which have been moved by the operation of

their appropriate key banks and give said arms 111 a still further movement thereby causing them through engagement with the bell cranks 107 to rock the latter about the shaft 105 against the tension of the spring 70 108 thereby effecting an engagement of the broad pinion 106 with the two indicating operating gears 100 and 102. This engagement of the broad pinions 106 with the indicating operating gears is maintained during the 75 adjustment of the actuators.

Just prior to the rocking movement of the shaft 101 any indicators which have been adjusted upon a previous operation of the machine are restored to normal position by the 80 following mechanism. All of the indicator gears 100 and 102 are formed with curved slots 122 formed on an arc concentric to the shaft 101. A bar 123 extends through said slots 122 and is carried by the pair of arms 85 124 loosely mounted on the rock shaft 101. The bar 123 is normally in the position shown in Fig. 1, but is adapted to be moved downwardly through the slots 122 at the very beginning of an operation of the machine and before the shaft 101 is rocked. The downward movement of the bar 123 is effected by a pitman 125 pivoted at its upper end to the left hand arm 124 and bifurcated at its lower end to straddle the operating 90 shaft 48. The pitman 125 carries an anti-friction roller 126, coöperating with the eccentric cam slot 127 formed in the box cam 128 fast to the main operating shaft 48. It will readily be seen that when an indicator 95 100 is adjusted to indicate an amount the indicating operating gear 102 will be moved in a counter-clockwise direction. Consequently when bar 123 is moved downwardly, as above described, it will engage the lower walls of 105 the slots 122 of the gears 102 of the adjusted indicators and move said gears 102 back to normal position. The cams 128 and 120 are so timed that the indicators will be restored to normal position by the cam 128 before the 110 cam 120 becomes effective to rock the shaft 101. Suitable means will, of course, be provided to retain the indicators in adjusted position during operations of the machine, but as such locking mechanism is old and well 115 known in the art, and forms no part of the present invention, the same has not been shown herein.

In order to prevent an accidental operation of the arms 111, the arms 116 carried 120 by the shaft 101 are curved so that upon the rocking movement of the shaft 101 they will engage the studs 112 of the adjusted arms 111 but will pass in front of the studs 112 of the arms 111 which have not been adjusted, consequently locking the latter against movement.

Printing mechanism.—The improved form of printing mechanism which forms part of the present invention is shown in 130

total printing position in Fig. 10. The rack teeth 27 formed on the actuators 25 also constantly engage with a plurality of racks segments 129 mounted fast on the right hand end of a series of nested sleeves 130. Mounted on the left hand end of the sleeves 130 are a series of pinions 131 each of which is constantly in engagement with a rack 132 formed on a rearwardly extending arm of a series of bell cranks 133 pivotally mounted on a stub shaft 134 carried by the left hand side frame. The forward arm of each of the bell cranks 133 is pivotally connected at 135 to the upper end of an actuating plate 136 formed with two sets of oppositely facing rack teeth 137 and 138. In the normal adjustment of the parts the rack teeth 137 are in engagement with a pinion 139 fast to a printing wheel 140. The printing wheel 140 is formed with two sets of type which may be of different form, one being used for the printing of items and the other for the printing of totals. The manner in which the type are arranged on the periphery of a printing wheel is indicated by the two sets of digits which have been placed for the purpose of illustration on the side of the wheel shown in Fig. 10. Upon an adjustment of the actuators 25 the pinions 131 are adapted to be rotated in the direction indicated by the full line arrow in Fig. 10, to effect a rotation of the printer wheel 140 in the direction of the full line arrow also shown in said figure. As the printing wheel is normally in zero printing position it will therefore be seen that the type used in the printing of items will be the lower set of type on the wheel 140. Adjacent the type wheels is a platen 141 adapted to cause an impression to be taken from the type wheels, 140 on a record strip 142. The platen 141 is carried by a bell crank 1420 pivoted on a stud 143 fast to the side frame of the machine. The downwardly extending arm 144 of the bell crank 142 is pivotally connected at 145 to the forward end of a link 146 the rearward end of which is pivoted at 147 to an arm 148 fast to a stud 149 on the frame of the machine. Adjacent the arm 149 and rigidly connected thereto is a rearwardly extending arm 150 pivoted at 151 to a pitman 152. Pitman 152 is bifurcated at its upper end to straddle main operating shaft 48 and carries an anti-friction roller 153 which is adapted to coöperate with the cam slot 154 formed in a box cam 155 fast on the main operating shaft 48. The cam slot 154 is so formed as to cause a single reciprocating movement of the pitman 152 to cause an actuation of the platen 141 at each operation of the machine, immediately following the adjustment of the actuators and prior to the time when the actuators are carried back to the normal zero position. The record strip 142 is led from a supply roll 156 carried by stud 157 on the frame of the machine, about two guiding studs 158 to a feeding and receiving roll 160 rotatably mounted on the stud 143. Fast to the receiving roll 160 is a ratchet disk 161 formed with one way ratchet teeth and adapted to coöperate with a feeding pawl 162 pivotally mounted on the arm 144 of the platen bell crank 142 and with a locking and lining pawl 163 pivoted on the frame of the machine. The purpose of the pawl 163 is to prevent any retrograde movement of the feeding ratchet 161. It will readily be seen that at each reciprocation of the platen bell crank 142 the feeding pawl 162 carried thereby will coöperate with the ratchet disk 161 to effect a slight rotation of the latter to an extent equal to the width of one of the teeth on the ratchet 161. This will be sufficient to move the record strip one space at each operation of the machine. Interposed between the record strip 142 and the type wheels 140 is an ink ribbon 164 passing from one roll 165 to a companion roll 166. Suitable feeding means for the ink ribbon 164 may be provided but as the same forms no part of the present invention no such feeding means have been shown in the drawings.

Total printing.—The foregoing description will suffice to set forth the mechanisms and constructions employed in the register for the printing of items of transactions. As it is desirable, however, to provide means for the printing of totals appearing on the totalizer and for resetting said totalizer to zero, a novel form of total printing and resetting mechanism has been provided in the present application together with suitable controlling mechanism for the same. Adjacent the bank of keys 20 is a total key 170 which is normally held in its outermost position by a spring 171 interposed between a pin 172 carried by said key and a flange 173 formed on the frame of the machine. The pin 172 is adapted to coöperate with a bevel slot 174 formed in a plate 175 adapted to slide on pins 176 and 177 carried by the frame of the machine. By reference to Fig. 14 it will be seen that the formation of the bevel cam slot 174 is such that the depression of the key 170 will cause a downward sliding movement of the plate 175. No mechanism has been shown for holding the total key in depressed position during an operation of the machine, but it will be readily understood that detent construction of the type illustrated in Fig. 2 will suffice to perform this function.

Carried by the plate 175 is a pin 1771 projecting laterally from said plate into a bifurcation 178 formed in an arm 179 rigidly connected to an arm 180, both of which arms are pivoted loosely on a stud 181 carried by the frame of the machine. At its upper end

the arm 180 is pivotally connected at 182 to a link 183 the rear end of which is pivoted at 184 to an arm 185 fast to the rock shaft 26. It will thus be seen that upon depression of a total key 170 a rocking movement of the shaft 26 will be effected. The shaft 26 carries a series of forwardly extending arms 186 (Fig. 4) one of which is provided for each of the actuators 25. Carried on the forward end of each of the arms 186 is an anti-friction roller 187 adapted to co-operate with the sliding arm 29 of its appropriate actuator 25. When the shaft 26 is rocked upon the depression of the key 170 it moves in a counter clockwise direction as viewed in Figs. 1, 4 and 14. This will cause a downward and rearward movement of the arm 186 and anti-friction roller 187, which roller will engage the upwardly projecting arm 39 of the bell crank 37. Upon the continued movement of the arm 186 the engagement of the roller 187 with the arm 39 will effect a rocking movement of the bell crank 37 to its pivot 40 thereby to withdraw the hooked portion 38 of said bell crank 37 from the position in which it engages the totalizer pinions 41 when the same are elevated into engagement with the teeth of the actuators.

Simultaneous with the rocking of the shaft 26 by the depression of the total key 170 connections are also operated which serve to effect the resetting of the totalizer wheels to zero position and positioning of the printer connections to print a total. The connections so operated are as follows: Pivoted at 188 to the cam plate 175 is a link 189 the lower end of which is pivoted at 190 to an arm 191 fast on a rock shaft 86. The rock shaft 86 as hereinbefore described, has rigidly mounted thereon a pair of arms 85 carrying the rod 84 which supports the forward ends of the transfer bars 81. When the key 170 is depressed the shaft 86 will be rocked in a counter clockwise direction as viewed in Figs. 3, 4 and 14, and it will thus be seen that the cross bar 84 will be lowered and consequently the lower ends of all of the transfer bars 81 will likewise be lowered thereby withdrawing the lugs 87 carried by said transfer bars 81, out of co-operative position throughout the constant movement of the totalizer. Also rigidly mounted on the shaft 86 is an arm 192 (Fig. 4) carrying at its upper end an anti-friction roller 193 projecting into an elongated slot 194 formed in the forward end of a curved track bar 195 loosely pivoted at its rear end on the shaft 54. It will thus be seen that when the shaft 86 is rocked as above stated the rearwardly and upwardly projecting arm 192 fast thereon will be moved toward a perpendicular position thus elevating the forward end of the curved track bar 195. The track bar 195 co-operates with the anti-

friction roller 196 fast on an arm 197 which is rigidly mounted on the rock shaft 44. Also rigidly mounted on the shaft 44 and projecting forwardly are a series of arms 198, one of which is provided for each of the totalizer pinions 61. At its forward end each of the arms 198 carries a pin 199 projecting beneath and supporting the forward end of a hooked finger 200 which is pivoted at 201 to the arm 198. When the forward end of the curved track bar 195 is elevated the shaft 44 will be rocked in a counter clockwise direction as viewed in Fig. 4 through the medium of an anti-friction roller 196 and arm 197. This, it will readily be seen, will lower the forward ends of the arms 198 and hooked finger 200 carried thereby. When the forward ends of the arms 198 are thus lowered, the pins 199 carried thereby are moved into the path of the enlarged teeth 65 of the totalizer pinions 41. When the machine is then operated to give the totalizer a constant movement, the hook arms 38 of the bell cranks 37 are displaced, as hereinabove described. Therefore the totalizer wheels will not be locked against rotation when they are elevated into engagement with the teeth 28 formed on the actuators. Consequently during the actuating stroke of the constant movement of the totalizer the pinions 41 will be permitted to rotate through their engagement with the rack teeth 28 until the enlarged teeth 65 of the totalizer pinions 61 engage the pins 199 carried by the arms 198, which engagement will be effective to prevent further rotation of the totalizer pinions 41. As the enlarged teeth 65 of said pinions 41 near the pins 199 in their rotating movement, said enlarged teeth 65 will engage the hooked ends of the fingers 200 carried by the arms 198 and will elevate the latter and pass beneath them. As soon, however, as the enlarged teeth strike the pins 199 the hook portion of the fingers 200 will drop down in front of the enlarged teeth, thereby preventing any retrograde or rebound movement of the same due to the sudden arrest of the rotating movement of the totalizer pinions. After the totalizer pinions are so arrested it will readily be seen that the continued operation of the actuating stroke of the constant movement of the totalizer will cause the actuators 25 to be moved until the end of the actuating stroke when the totalizer pinions 41 are again disengaged from the teeth 28 of the actuators. Upon the restoring movement of the totalizer it will be remembered that the transfer bars 81 have been rocked out of operative position and consequently any transfer devices which were tripped during the resetting movement of the totalizer pinions will not be operated but upon the completion of the restoring movement of the totalizer the arms 970 will be effective to en-

gage the hooks 68 of the transfer devices to restore said transfer device to normal position.

As shown in Figs. 10 and 14 the left hand end of the rock shaft 86 has rigidly mounted thereon an arm 202 shown in detail in Fig. 12, which arm 202 carries at its upper end a plurality of forked arms 203. The arms 203 are formed with a large V-shaped notch, the forward wall of which normally engages a stud 204 carried by the lower ends of the actuating plates 136, thereby normally holding the racks 137 in engagement with the type wheel pinions 139. When, however, the shaft 86 is rocked in the direction of the arrow shown in Fig. 10 the rear wall of the V-shaped notch will effect a rocking movement of the actuating plate 136 about the pivots 135 thereby causing the racks 138 to engage with the pinions 139 carried by the type wheels as shown in said figure. It will thus be seen that upon the adjustment of the actuators during the latter part of the actuating stroke of the constant movement of the totalizer, the type wheels will be rotated in a direction reverse to that in which it was moved during the printing of items. Thus the upper set of type of the type wheels will be brought into operation and the printing of totals will be effected thereby. At the end of the operation of the machine when the total key 170 is released and allowed to move to normal outer position, all of the parts controlled thereby will also be allowed to move to normal position ready for an item recording operation.

It will readily be seen that upon the operation of printing a total, when the total key 170 is depressed, no depression of any of the amount keys 20 should take place. Therefore as none of said keys are depressed the indicator connections above described will not be operated and all of the indicators will remain disconnected from the actuators 25. If an amount was indicated on the operation of the machine immediately preceding, the total printing operation has no effect whatsoever on the indicators other than the regular restoring movement, which is effected at the very beginning of each operation of the machine.

A novel form of means is provided to overcome the inertia and momentum of the totalizer carrying frame 45. Pivotedly mounted on the cross shaft 26 is a plate 261 having a rearwardly extending arm 262 carrying an anti-friction roller 263 projecting into a cam groove 264 formed in a box cam 265 rigidly mounted on the rotation shaft 48. The plate 261 also has two downwardly extending arms 266 and 267 which are adapted to coöperate with a projecting end of the shaft 44 in the following manner. As shown in Figs. 1 and 3 the arm 266 normally rests against the shaft 44. The slot

in the cam 265 is so formed as to coöperate with the cam 51 to assist in the beginning of the actuating stroke of the totalizer carrying frame. As soon as the cam 51 has been moved to an extent sufficient to begin the actuating stroke of the totalizer carrying frame, the cam 265 will also be moved to an extent sufficient to begin a movement of the plate 261 and consequently through the engagement of the arm 266 with the projecting end of the shaft 44 it will be seen that this movement of the plate 261 will assist in the beginning of the actuating stroke of the totalizer carrying frame. Near the end of the actuating stroke of the totalizer frame the shaft 44 will engage the arm 267 of the plate 261. Just at this time the cam 265 will become effective to rock the plate 261 to a further slight extent in the same direction as its former movement, thereby assisting the cam 51 in arresting the momentum of the totalizer carrying frame 45. The cams 265 and 51 are further timed relative to each other so that the arm 267 of the plate 261 will also assist on the beginning of the restoring stroke of the totalizer carrying frame and at the completion of the constant movement the shaft will strike the arm 266 of the plate 261 at which time the plate 261 will be given further slight movement in a counterclockwise direction.

By the use of the above mechanism it will readily be seen that the load of starting and stopping the totalizer carrying frame 45 is distributed between the two cams 51 and 265 and their connecting mechanisms.

General operation.—The general operation of the machine hereinbefore described is as follows: If an item is to be entered upon the totalizer and printed upon the record strip, the keys 20 are depressed to represent the item to be recorded. If, for example, the amount "3" is to be entered upon the totalizer and recorded on the record strip, the third key from the top of the series of keys 20, as shown in Fig. 1, is depressed. When the key is depressed, pin 23 carried by the key will be engaged by the detent plate 21 to hold the key in depressed position. Upon the depression of the key, the cam plate 24 will be moved downwardly thereby rocking the indicator connections to establish a coöperative relation between the indicator and the actuator appropriate to the units bank of keys. Upon the operation of the main operating mechanism which may be, as hereinbefore stated, of any preferred form, the shaft 48 will be given a single rotation and the totalizer carrying frame will be given a constant reciprocating movement. Immediately upon the beginning of the operation of the machine the totalizer will be rocked into engagement with the rack formed on the actuators 25. When the totalizer is so

rocked the appropriate totalizer elements 41 will be engaged by the hooks 38 which are pivotally mounted on the actuators. The engagement of the hooks with the totalizer wheels will prevent any rotation of a totalizer element during the actuating stroke of the constant movement of the totalizer carrying frame unless said hooks are disengaged. As soon however as the units actuator has been moved to an extent sufficient to bring the arm 30 carried by the actuator into the engagement with the depressed key the hook 38 will be disengaged from the units totalizer wheel and the further movement of the units actuator will be prevented. Consequently the totalizer element will be rotated during the remaining portion of the actuating stroke of the totalizer frame in its reciprocation. It will readily be seen that as the key appropriate to the amount "3" is the third key from the top, the actuator will be given seven steps of movement without any rotation of the totalizer wheel. Upon the completion of the seven steps of movement of the actuator the hook 38 will be disengaged as hereinbefore mentioned, and the totalizer wheel will be turned three steps during the remaining three steps of movement of the actuating stroke of the totalizer frame. It will thus be seen that the actuator is adjusted to an extent complementary to the amount added on the totalizer.

In order to indicate the proper amount of the indicator the numbers are arranged on the indicator in the reverse order with a blank space normally exposed so that seven steps of movement of the actuator will indicate the number three on the same. Upon the beginning of the restoring stroke of the totalizer carrying frame the totalizer elements are lowered out of engagement with the actuator racks and the rollers 88 of the transfer members 71 will be lowered to a position wherein they will be engaged by the transfer lugs 87 carried by the transfer plates 81 during the restoring stroke of the totalizer carrying frame, thereby turning in any transfers which were tripped during the actuating stroke of the totalizer and also enter transfers which are tripped coincident to the turning in of the transfer on a wheel of lower order. Upon the completion of the restoring stroke of the totalizer carrying frame all of the transfers which were tripped and operated during the reciprocation of the same will be restored to normal position by their engagement with the relatively stationary arms 97.

When it is desired to print a total the total key 170 is depressed and the regular operation of the operating means is effected. When the key 170 is depressed the connections hereinabove described will act to rock the shafts 26 and 86. When the shaft 26 is rocked by the depression of the total key

the frames 186 carried thereby will move downward and rock the hooks 38 out of the position to engage the totalizer elements. Upon the rocking of the shaft 86, the transfer plates 81 are dropped down out of the path of the transfer devices and the track bar 195 raised to cause pin 199 to move down into the path of the enlarged teeth carried by the totalizer elements. If the amount "3" appears on the units totalizer wheel it will readily be seen that as the totalizer wheel is turned in an additive direction when restoring to zero, the totalizer element will rotate during the first seven steps of movement of the totalizer carrying frame on its actuating stroke. This will bring the enlarged tooth 65 of the totalizer element to a position wherein it will be engaged by the pin 199 thereby preventing any further rotation of the totalizer element. Consequently during the remaining three steps of movement of the totalizer carrying frame the actuator will be given three steps of movement. As the numbers on the indicator are arranged in a reverse order, as hereinabove mentioned, it is therefore necessary to provide the normally open connections between the actuator and the indicator so that in case of printing a total the indicators will not be moved. When clearing the amount "3" as above stated, it would readily be seen that if the indicators were normally connected to the actuators the indicator would be given three steps of movement thereby bringing the number seven to indicating point, which would be incorrect, as it would not represent the total which was cleared from the totalizer. The connections are therefore provided to prevent any movement of an indicator unless a key in its appropriate bank has been depressed. As the transfer bars are lowered out of operative position upon depression of the total key, it will readily be seen that any transfers which are tripped during the restoring movement of the totalizer elements will not be returned to turn in a transfer, and upon the completion of the restoring stroke of the totalizer carrying frame those transfer elements which are tripped will be restored to normal position without effecting a transfer.

From the above description the necessity of providing two sets of type on the printing wheels and for rotating the same in opposite directions during the item printing and total printing operations will be obvious. It will be remembered that in entering an item in the machine the actuators are moved to an extent complementary to the value of the item to be entered. When the counter is to be reset and a total to be printed, however, the totalizer elements are rotated in the same direction as they are rotated in entering an item. Consequently

the actuators are adjusted to an extent in direct ratio to the amount appearing on the totalizer. For example, if the units totalizer element stood at zero and "3" is 5 to be entered on the totalizer, it will readily be seen that the actuators will be given seven steps of movement and will then actuate the totalizer element three steps during the remaining portion of the actuating stroke 10 of the totalizer frame. If it is then desired to restore the units totalizer element to zero, and to print the amount cleared, the wheel will be rotated seven steps until the enlarged tooth strikes the stop which 15 is brought into operative position upon the depression of the total key. Consequently the actuator will remain idle during the first seven steps of movement of the totalizer frame and will be adjusted during the 20 remaining three steps of movement of the totalizer frame. The printing wheel therefore would be given seven steps of movement to print number "3" on an item entering operation, while it would only move 25 three steps when clearing the amount "3" from the totalizer. It is for this reason that the duplicate sets of type are provided, and the numbers range in opposite order from the point which is normally adjacent the 30 printing platen.

While the form of mechanism herein shown and described is admirably adapted to fulfil the objects primarily stated, it is to be understood that it is not intended to 35 confine the invention to the one form of embodiment herein shown and described as it is susceptible of embodiment in various forms, all coming within the scope of the claims which follow:

40 What is claimed is:

1. In a machine of the class described, the combination with a series of manipulative amount determining devices, of a differentially movable gear element, a second 45 gear element adjacent thereto, a rotatable accounting element having a stationary pivot and engaging said second gear element, and a bodily movable coupling pinion normally disconnected from said gear elements and adapted to be adjusted by an 50 operation of any of said devices for enabling the engagement of said coupling pinion with both of said gear elements, whereby movement of the first mentioned 55 gear element is transmitted to the accounting element.

2. In a machine of the class described, the combination with manipulative amount determining means, of actuators controlled 60 in extent of movement by said manipulative means, indicating means for indicating at each operation the amount represented by the operated manipulative means and adapted for operation by the actuators, but 65 normally disconnected therefrom, and means

controlled by said manipulative means for establishing a coöperative relation between said indicating means and actuator.

3. In a machine of the class described, the combination with a plurality of banks 70 of keys, an actuator appropriate to each bank, indicators, for indicating at each operation the amount represented on the operated manipulative means, one being appropriate to each actuator but normally disconnected therefrom and means controlled by the operation of a key in any bank for establishing a coöperative relation between its appropriate actuator and indicator.

4. In a machine of the class described, 80 the combination with a main operating mechanism, of a plurality of banks of keys, an actuator appropriate to each bank, an indicator appropriate to each actuator but normally disconnected therefrom, means 85 controlled by the operation of a key in any bank for enabling the establishment of a coöperative relation between its appropriate actuator and indicator, and means effective upon an operation of the main operating 90 mechanism for effecting said coöperative relation.

5. In a machine of the class described, the combination with a plurality of banks of keys, an actuator appropriate to each bank, 95 an indicator appropriate to each actuator but normally disconnected therefrom, means controlled by the operation of a key in any bank for establishing a coöperative relation between its appropriate actuator and indicator, and a totalizer certain movements of 100 which are adapted to adjust said actuator and indicator.

6. In a machine of the class described, the combination with a main operating mechanism, of a plurality of banks of keys, an actuator appropriate to each bank, an indicator appropriate to each actuator but normally disconnected therefrom, means controlled by the operation of a key in any bank for enabling the establishment of a coöperative relation between its appropriate actuator and indicator, means effective upon an operation of the main operating mechanism for effecting said coöperative relation, 110 and a totalizer certain movements of which are adapted to adjust the actuator and connected indicators.

7. In a cash register the combination with a main operating mechanism, of a series of oscillatory actuators, a series of depressible keys for predetermining the extent of movement of the actuators, indicating mechanism adapted for operation by the actuators but normally disconnected therefrom, means 120 controlled by the keys for enabling a coöperative relation between the indicating mechanism and actuators, and devices operated by the main operating mechanism to effect the said coöperative relation.

8. In a cash register, the combination with a main operating mechanism, of a plurality of series of depressible keys arranged in banks, an oscillatory actuator for each bank adapted to be given first an operating and then a restoring stroke whenever a key in its appropriate bank has been depressed, a series of oscillatory indicators each appropriate to one of said actuators adapted to be operated thereby but normally disconnected therefrom, a plurality of devices one for each bank operable to establish a coöperative relation between its appropriate indicator and actuator, connections controlled by the keys of each bank for enabling the operation of its appropriate device, and means operated by the main operating mechanism for effecting an operation of the devices so enabled and holding them in operated position during the operating stroke of the actuator.
9. In a cash register, the combination with a main operating mechanism, of a plurality of series of depressible keys arranged in banks, an oscillatory actuator for each bank adapted to be given first an operating and then a restoring stroke whenever a key in its appropriate bank has been depressed, a series of oscillatory indicators each appropriate to one of said actuators adapted to be operated thereby but normally disconnected therefrom, a plurality of devices one for each bank operable to establish a coöperative relation between its appropriate indicator and actuator, connections controlled by the keys of a bank for enabling the operation of its appropriate device, means operated by the main operating mechanism for effecting an operation of the devices so enabled and holding them in operated position during the operating stroke of the actuator, and means also operated by the main operating mechanism for restoring all of the previously operated indicators to normal zero position at the beginning of each operation of the machine and before any of said devices have been operated.
10. In a cash register, the combination with a main operating mechanism, of a plurality of series of depressible keys arranged in banks, an oscillatory actuator for each bank adapted to be given first an operating and then a restoring stroke whenever a key in its appropriate bank has been depressed, a series of oscillatory indicators each appropriate to one of said actuators adapted to be operated thereby but normally disconnected therefrom, a plurality of devices one for each bank operable to establish a coöperative relation between its appropriate indicator and actuator, connections controlled by the keys of each bank for enabling the operation of its appropriate device, means operated by the main operating mechanism for effecting an operation of the devices so enabled and

holding them in operated position during the operating stroke of the actuator, and for locking in normal position all of said devices which have not been so enabled.

11. In a machine of the class described, the combination with a series of differentially adjustable actuators, manipulative amount determining means for controlling the movements of the actuators, a movable frame, a totalizer carried thereby, means for giving the frame a constant movement at each operation of the machine, and connections whereby the movement of the totalizer effects the adjustment of the actuators.

12. In a machine of the class described, the combination with a series of differentially adjustable racks, of a movable frame, a totalizer carried thereby, means for giving the frame a constant movement at each operation of the machine, connections whereby the movement of the totalizer effects the adjustment of the actuators, and manipulative amount determining means for limiting the extent of said adjustment and disabling said connections.

13. In a machine of the class described, the combination with a series of differentially adjustable actuators, of a movable frame, a totalizer carried thereby, means for giving the frame a constant movement at each operation of the machine, connections whereby the movement of the totalizer effects the adjustment of the actuator, means for limiting the extent of said adjustment, and means for disabling said connections.

14. In a machine of the class described, the combination with a series of differentially adjustable racks, of a movable frame, a totalizer carried thereby, means for giving the frame a constant movement at each operation of the machine, connections whereby the movement of the totalizer effects the adjustment of the racks, and means for disabling said connections and differentially limiting the movement of said racks whereby a greater or less number of teeth thereof will remain in the continued path of travel of the register according to the amount to be registered.

15. In a machine of the class described, the combination with a series of differentially adjustable racks, of a movable frame, a series of totalizing elements carried thereby, one for each rack, means for giving said frame a constant movement at each operation of the machine, connections intermediate each of said racks and its appropriate element whereby said racks may be adjusted by the movement of the frame, and means for differentially controlling the extent of adjustment of the racks.

16. In a machine of the class described, the combination with a series of differentially adjustable racks, of a movable frame, a series of totalizing elements carried thereby,

- one for each rack, means for giving said frame a constant movement at each operation of the machine, connections intermediate each of said racks and its appropriate element whereby said racks may be adjusted by the movement of the frame, and means for differentially controlling the extent of adjustment of the racks and disabling said connections.
- 10 17. In a machine of the class described, the combination with a series of differentially adjustable racks, of a movable frame, a series of totalizing elements, carried thereby, one for each rack, means for giving said frame a constant movement at each operation of the machine, connections intermediate each of said racks and its appropriate element whereby said racks may be adjusted by the movement of the elements and for disabling said connections whereby a greater or less number of teeth thereof will remain in the path of travel of their appropriate elements during the continued movement of the frame.
- 15 18. In a machine of the class described, the combination with a series of differentially adjustable actuators, of a totalizer, means for giving said totalizer a constant excursion at each operation of the machine, and connections whereby said totalizer will act to adjust the actuators during a portion of its excursion and be operated by the latter during the remaining portion of its excursion.
- 20 19. In a machine of the class described, the combination with a series of differentially adjustable actuators, of a totalizer, means for giving said totalizer constant excursion at each operation of the machine, connections whereby said totalizer will act to adjust the actuators during a portion of its excursion and be operated by the latter during the remaining portion of its excursion, and manipulative means for controlling the extents of said portions in the excursion.
- 25 20. In a machine of the class described, the combination with a series of differentially adjustable actuators, of a totalizer, means for giving said totalizer a constant excursion at each operation of the machine, and connections whereby the movement of the totalizer effects the adjustment of the actuators.
- 30 21. In a machine of the class described, the combination with a series of differentially adjustable actuators, of a totalizer, means for giving said totalizer a constant excursion at each operation of the machine, connections whereby the movement of the totalizer effects the adjustment of the actuators, and means for controlling the extent of said adjustment and disabling said connections.
- 35 22. In a machine of the class described, the combination of an operating mechanism, of a series of racks, a totalizer arranged to be moved to adjust the racks and be operated by them, and means connected to the operating mechanism for moving the totalizer into and out of operative relation with the racks.
- 40 23. In a machine of the class described, the combination with a series of racks, of a totalizer arranged to be moved to adjust the racks and be operated by them when adjusted, all as an incident to the recording of an item.
- 45 24. In a machine of the class described, the combination with a totalizer element, of an actuator therefor adjusted by a movement of the totalizer element and adapted to actuate said element when so adjusted, all as an incident of the recording of an item.
- 50 25. In a machine of the class described, the combination with a totalizer element of an actuator therefor adjusted by a movement of the totalizer element to effect the actuation of said element, all as an incident to the recording of an item.
- 55 26. In a machine of the class described, the combination with a series of racks, of a totalizer arranged to be moved to adjust the racks and be operated by them when adjusted, and manipulative devices for controlling the extents of said adjustment and operation.
- 60 27. In a machine of the class described, the combination with an actuator, of a totalizer element, and means for moving the totalizer element to adjust the rack and be operated thereby, all as an incident to the recording of an item.
- 65 28. In a machine of the class described, the combination with an actuator, of a totalizer element, means for moving the totalizer element to adjust the actuator and be operated thereby, and manipulative devices for controlling extents of said adjustment and operation.
- 70 29. In a machine of the class described, the combination with a main operating mechanism, of an actuator, a totalizer element, means operated upon each operation of the main operating mechanism to move the totalizer element to adjust the actuator and be operated thereby, and manipulative devices operable preliminarily to predetermine the extents of said adjustment an operation.
- 75 30. In a machine of the class described, the combination with an actuator, of a totalizer element, means for giving the said element a constant movement at each operation of the machine, a normally effective means for connecting said actuator and element whereby a portion of the constant movement of the element will effect an adjustment of the actuator, and manipulative devices for disabling said connecting means at any desired point in the movement of the element, whereby the remainder of said constant movement of the element will effect an operation thereof by the actuator.

31. In a machine of the class described, the combination with an actuator, of a totalizer element, means for giving the said element a constant movement at each operation of the machine, a normally effective means carried by the actuator and engaging said element whereby a portion of the constant movement of the element will effect an adjustment of the actuator, a series of manipulative devices, and means carried by the actuator and controlled by said manipulative devices to arrest the movement of the actuator and disable said engaging means at any desired point, whereby the remainder 5 of said constant movement of the element will effect an operation thereof by the actuator. 70
32. In a machine of the class described, the combination with a series of racks, of a totalizer arranged to be given a constant movement to adjust said racks differentially, and manipulative means controlling the extent of said adjustment. 75
33. In a machine of the class described, the combination with a totalizer element, of an actuator therefor, adjusted by a movement of the totalizer element and adapted to actuate said element when so adjusted, and manipulated means controlling the extent of said adjustment. 80
34. In a machine of the class described, the combination with a totalizer element, of an actuator therefore adjusted by a movement of the totalizer element to effect the actuation of said element and manipulative means controlling the extent of said adjustment. 85
35. In a machine of the class described, the combination with a totalizer mounted in a movable frame, of an actuator for the totalizer, connections intermediate the totalizer and actuator, means for giving the said frame a constant movement at each operation of the machine, and manipulative 90 means for differentially disabling said connections. 95
36. In a machine of the class described, the combination with a totalizer mounted in a movable frame, of an actuator for the totalizer, normally effective connections intermediate the totalizer and actuator, means for giving the said frame a constant movement at each operation of the machine, and manipulative means for disabling said connections. 100
37. In a machine of the class described, the combination with a totalizer mounted in a movable frame, of an actuator for the totalizer, latching means carried by the actuator, means for moving said totalizer into engagement with the actuator and latching means, driving means for giving said frame a constant movement at each operation of the machine thereby adjusting said actuator during a portion of said constant move- 105
- ment, and manipulative means operable differentially to disable said latching means and arrest the actuator whereby said totalizer will be actuated on the continued movement of said frame. 110
38. In a machine of the class described, the combination with a totalizer, of an actuator therefor, means for giving said totalizer a constant movement at each operation of the machine, a latch carried by the actuator and adapted to engage the totalizer whereby said actuator will be adjusted during a portion of said constant movement. 115
39. In a machine of the class described, the combination with a totalizer, of an actuator therefor, means for giving said totalizer a constant movement at each operation of the machine, a latch carried by the actuator and adapted to engage the totalizer whereby said actuator will be adjusted during a portion of said constant movement, and manipulative devices operable differentially to disable said latch and arrest said actuator whereby said totalizer will be actuated on the continued movement of said frame. 120
40. In a machine of the class described, the combination with a totalizer element, of an actuator therefor having a rack formed thereon, means for giving said totalizer a constant degree of movement at each operation of the machine, means for moving the totalizer into engagement with the actuator at the beginning of said constant movement, a latch carried by the actuator adjacent the point of engagement and adapted to prevent rotation thereof whereby an adjustment of the actuator will be effected during a portion of said constant movement, and manipulative devices differentially operable to disable said latch and arrest the actuator whereby said totalizer element will be rotated during the remaining portion of said constant movement. 125
41. In a machine of the class described, the combination with an accounting element, of an actuator therefor adapted to be adjusted thereby and operate the same when adjusted, all as an incident to the recording of an item. 130
42. In a machine of the class described, the combination with an accounting element mounted in a movable frame, an actuator for said element, means for giving said frame a constant degree of reciprocation at each operation of the machine whereby said actuator will be adjusted differentially and then actuate said element during the movement of the frame in one direction, and means carried by the frame for restoring the actuators to normal position on the return movement of the frame. 135
43. In a machine of the class described, the combination with a series of differentially adjustable actuators, manipulative

amount determining means for controlling the movement of the actuators, a movable frame, a totalizer carried thereby, means for giving the frame and totalizer a constant degree of reciprocation at each operation of the machine, connections whereby the movement of the totalizer effects the adjustment of the actuators during the movement of the frame and totalizer in one direction, and means carried by the frame for restoring the actuators to normal position during the movement of the frame in the other direction.

44. In a machine of the class described, 15 the combination with a series of differentially adjustable racks, of a movable frame, a totalizer carried thereby, means for giving the frame and totalizer a constant degree of reciprocation at each operation of the machine, connections whereby the movement of the totalizer effects the adjustment of the actuators during the movement of the frame and totalizer in one direction, manipulative devices for differentially limiting 20 the extent of said adjustment and disabling said connections, and means carried by the frame for restoring the actuators to normal position during the movement of the frame in the other direction.

25 45. In a machine of the class described, the combination with a totalizing mechanism, of indicating mechanism, and connections whereby said mechanisms are given extents of movement complementary to each 30 other to register and indicate like amounts.

46. In a machine of the class described, the combination with a totalizing mechanism, of indicating mechanism, and connections controlled by the totalizing mechanism whereby said mechanisms are given 40 extents of movement complementary to each other to register and indicate like amounts.

45. 47. In a machine of the class described, the combination with a totalizing mechanism, of indicating mechanism, and connections adjusted by the totalizing mechanism whereby said mechanisms are given 50 extents of movement complementary to each other to register and indicate like amounts.

55. 48. In a machine of the class described, the combination with a totalizer, of indicating mechanism, and connections whereby said indicating mechanism is actuated by the movement of the totalizer and a series 55 of keys for limiting the extent of said actuation.

49. In a machine of the class described, the combination with a totalizer, of indicating mechanism, connections intermediate the 60 totalizer and indicating mechanism whereby the latter is actuated by a movement of the former, and manipulative devices for controlling the extent of said adjustment.

50. In a machine of the class described, 65 the combination with a totalizer element, of

an actuator therefor adapted to be adjusted by and then operate the same, and an indicator adapted to be operatively connected with the actuator during its adjustment.

51. In a machine of the class described, 70 the combination with a totalizer element, of an actuator therefor adapted to be adjusted by and then operate the same, an indicator adapted to be operatively connected with the actuator during its adjustment, and 75 manipulative devices for effecting the operative connection between the indicator and actuator and differentially controlling the extent of adjustment of the actuator.

52. In a machine of the class described, 80 the combination with a totalizer element, of an actuator therefor adapted to be adjusted thereby and then operate the same, an indicator adapted to be operatively connected with the actuator during its adjustment, 85 and manipulative devices for controlling the operative connections between the indicator and actuator and the extent of adjustment of the actuator.

53. In a machine of the class described, 90 the combination with a totalizer adapted to be given a constant movement at each operation of the machine, of a main operating device for effecting said constant movement, an actuator for the totalizer adapted to be 95 adjusted thereby and then to operate the same, manipulative means for controlling the extent of adjustment of the actuator, an indicator, connections intermediate the indicator and actuator and under control 100 of the manipulative means for establishing a coöperative relation between the indicator and actuator, and means operated by the main operating device for operating said intermediate connections to establish said 105 coöperative relation.

54. In a machine of the class described, the combination with an actuating rack, of a totalizer element having a constant movement relative thereto, an adjustable track 110 for confining the movement of said totalizer element, means for adjusting said track relative to the rack to effect an engagement therewith of the totalizer element, a latch carried by the actuator and adapted to prevent rotation of the totalizer element during a portion of said constant movement whereby the actuator will be adjusted by the movement of the element, and manipulative means for disabling said latch and arresting the actuator whereby the element will be actuated during the remainder of said movement.

55. In a machine of the class described, 125 the combination with type carriers for recording upon a record strip items and the totals thereof, of a plurality of totalizer elements, differentially movable devices normally connected to the type carriers by one face of double faced rack plates operatively 130

- connected with the differentially movable devices whereby said type carriers are moved in one direction in recording items, a total key and connections for shifting said 5 rack plates to positions wherein the other faces of the rack plates will operatively engage the type carriers to move the same in the opposite direction for printing the total.
56. In a machine of the class described, 10 the combination with a plurality of actuators, of a totalizer comprising a plurality of rotatable elements, means for giving said totalizer a constant operating movement at each operation of the machine, means for 15 moving said elements into engagement with the actuators at the beginning of said constant movement, latching means for preventing rotation of the elements when so engaged whereby the actuators will be adjusted 20 during a portion of said movement and manipulative devices for disabling said latching means and arresting the actuators whereby said elements will be rotated during the remaining portion of said movement.
57. In a machine of the class described, 25 the combination with a plurality of actuators, of a totalizer comprising a plurality of rotatable elements, means for giving said totalizer a constant operating movement relative to the actuators at each operation of the machine, means for moving said elements into engagement with the actuators at the beginning of said constant movement, latching means carried by the actuator for preventing rotation of said elements when so engaged whereby the actuators will be adjusted 30 during a portion of said movement, and manipulative devices adapted to disable said latching means and differentially arrest the 35 adjustment of the actuators whereby said elements will be rotated different extents during the remaining portion of said movement.
58. In a machine of the class described, 40 the combination with a plurality of actuators, of a totalizer comprising a plurality of rotatable elements, means for giving said totalizer a constant reciprocation at each 45 operation of the machine comprising an operating and restoring stroke, means for maintaining said elements in engagement with the actuators during the operating stroke and out of engagement during the restoring stroke, transfer devices intermediate all of said elements adapted to be tripped by the completion of a rotation of any of 50 said elements, normally stationary lugs adapted to engage and operate the tripped transfer devices during the restoring stroke, 55 relatively stationary means for resetting the tripped transfer devices at the end of the restoring stroke, and means for moving said lugs out of engaging position when printing totals.
59. In a machine of the class described, 60 the combination with a plurality of actuators, of a totalizer comprising a plurality of rotatable elements, means for giving said totalizer a constant reciprocation at each operation of the machine said reciprocation 65 comprising operating and restoring strokes, means for maintaining said elements in engagement with the actuators during the operating stroke and out of engagement there- 70 with during the restoring stroke, latching means normally in position to prevent rotation of said elements when so engaged whereby in recording items the actuators will be adjusted during the first portion of 75 said operating stroke, controlling means for disabling said latching means and arresting said actuators whereby said elements will be actuated during the latter remaining portion of said operating stroke, a total key operable as a preliminary to a reciprocation 80 of the totalizer for disabling said latching means and positioning an obstructing means whereby said elements will be reset to zero and then arrested during the first portion 85 of said operating stroke and act to adjust the actuators thereafter during the remaining portion of the operating stroke.
60. In a machine of the class described, 90 the combination with a series of differentially adjustable actuators, of a totalizer, 95 means for giving said totalizer a constant excursion at each operation of the machine, connections whereby said totalizer will act to adjust the actuators during a portion of its excursion and be operated by the latter 100 during the remaining portion of its excursion, a total key and means controlled thereby for disabling said connections whereby said totalizer will be reset to zero during a portion of the excursion and then adjust 105 the actuators during the remaining portion of the excursion.
61. In a machine of the class described, 110 the combination with an operating mechanism, of a series of racks, a totalizer ar- 115 ranged to be moved relative to the racks, and normally thereby adjust them and be operated by them, a total key and connec- 120 tions controlling the totalizer whereby the same will be reset by said relative movement and then adjust the actuators.
62. In a machine of the class described, 125 the combination with an actuator, of a totalizer element, means for giving the element a constant movement relative to the actuator at each operation of the machine, a normally effective means for connecting said actuator and element whereby a portion of the constant movement of the element will effect an adjustment of the actuator and the remaining portion of the actuation of the element by the adjusted actuator, a total key and connections for disabling said connecting means

and controlling the element whereby said element will be reset by the first portion of said movement and will act to adjust the actuator during the remaining portion of

5 the said movement.

63. In a machine of the class described, the combination with a totalizer, of an actuator therefor, means for giving said totalizer a constant movement at each operation 10 of the machine, a latch carried by the actuator and adapted to engage the totalizer whereby said actuator will be adjusted during a portion of said constant movement, manipulative devices operable differentially 15 to disable said latch and arrest said actuator whereby said totalizer will be actuated on the continued movement of the frame, and a total key and connection controlled thereby for disabling said latch and controlling the 20 totalizer, whereby the latter will be reset by the first portion of said movement and will act to adjust the actuator during the remaining portion of said movement.

64. In a machine of the class described, 25 the combination with a series of differentially adjustable actuators, of a totalizer, means for giving the totalizer a constant excursion at each operation of the machine, connections whereby said totalizer will act to 30 adjust the actuators during a portion of its excursion and be operated by the latter during the remaining portion of its excursion, type carriers, and connections intermediate 35 the actuators and type carriers whereby the latter will be adjusted upon the adjustment of the actuators.

65. In a machine of the class described, the combination with a differentially adjustable actuator, a type carrier having two 40 sets of type, impression taking means for taking an impression from any of said type, adjustable connections intermediate the actuator and type carriers normally in condition to adjust one set of type relative to 45 the impression taking means, and a total key for adjusting said connections whereby the other set of type will be adjusted relative to said impression taking means.

66. In a machine of the class described, 50 the combination with a main operating device, of a member adapted to be given a constant reciprocation at each operation of the main operating device, connections intermediate the main operating device and 55 the member for effecting said constant movement and an auxiliary device operated by the main operating device and adapted to assist said connections in the beginning of the movement of the member in each direction and arresting said members at the end of said movements.

67. In a machine of the class described, the combination with a series of racks, of a totalizer arranged to be moved to adjust

the racks and then be operated by them in 65 the entering of an item and to be operated by the racks and then adjust them to turn the totalizer to zero.

68. In a machine of the class described, the combination with a series of racks, of 70 a totalizer arranged to be moved to adjust the racks and then be operated by them in the entering of an item and to be operated by the racks and then adjust them to turn the totalizer to zero, and type carriers and 75 connections adjusted by said racks to print the items entered on the totalizer in item entering operations and the total of the items when the totalizer is turned to zero.

69. In a machine of the class described, 80 the combination with a totalizer element, of an actuator therefor adjusted by a movement of the totalizer element and adapted to actuate said element when so adjusted to enter an item and adapted to actuate the 85 totalizer element and then be adjusted thereby to turn the element to zero.

70. In a machine of the class described, the combination with a totalizer element, of an actuator therefor adapted to turn the 90 element to zero by a movement of the element.

71. In a machine of the class described, the combination with an accounting element, of an actuator therefor adapted to 95 turn the element to zero by a movement of the element.

72. In a machine of the class described, the combination with a series of racks, of a totalizer arranged to be moved to be operated by the racks to reset said totalizer to zero and then adjust the racks to an extent commensurate with the total cleared from the totalizer.

73. In a machine of the class described, 105 the combination with a series of racks, of a totalizer arranged to be operated by the racks by a movement of the totalizer to extents determined by the totalizer and to then adjust the racks.

74. In a machine of the class described, the combination with a rack, of a totalizer arranged to be moved an invariable extent to be operated by the racks and then adjust the racks, and means for moving the totalizer an invariable extent.

75. In a machine of the class described, the combination with a series of racks, of a totalizer arranged to be moved to adjust the racks and then be operated by them in 120 the entering of an item and to be operated by the racks and then adjust them to turn the totalizer to zero, and manipulative means for controlling the extent of operation of the racks to enter an item, the totalizer being designed to control their extent of operation when the totalizer is turned to zero.

76. In a machine of the class described,

the combination with an operating mechanism, of a series of racks, a totalizer arranged to be moved to be operated by the racks and then adjust the latter, and means connected to the operating mechanism for moving the totalizer into and out of operative relation with the racks.

77. In a machine of the class described, the combination with a series of differentially adjustable actuators, of a totalizer, means for giving said totalizer a constant excursion at each operation of the machine, connections whereby the movement of the totalizer effects the adjustment of the actuators, and means controlled by the totalizer for controlling the extent of said adjustment and disabling said connections.

78. In a machine of the class described, the combination with a series of differentially adjustable actuators, of a totalizer, means for giving said totalizer a constant excursion at each operation of the machine, and connections whereby said totalizer will be actuated by the actuators during a portion of its excursions and adjust the latter during the remaining portion of its excursion.

In testimony whereof I affix my signature in the presence of two witnesses.

HAAKON A. MARTIN.
